UNITED STATES PATENT OFFICE.

JOSEPH L. WALKER, OF BATON ROUGE, LOUISIANA, ASSIGNOR TO K-D BARREL AND HAMPER CO., OF BATON ROUGE, LOUISIANA.

BARREL-FORMING MACHINE.

Application filed June 11, 1921. Serial No. 476,854.

To all whom it may concern:

Be it known that I, JOSEPH L. WALKER, a citizen of the United States, residing at Baton Rouge, in the parish of East Baton 5 Rouge and State of Louisiana, have invented a new and useful Barrel-Forming Machine, of which the following is a specification.

This invention relates to machines for 10 forming barrels, one of its objects being to provide a machine to which the assembled hoops and staves or strips are fed, this machine operating to grip one of the staves and to then bend the assembled hoops and staves 15 to cylindrical form so as to bring the ends of the hoops to position where they can be secured quickly and accurately.

Another object is to provide a machine 20 of this type having means for holding the parts firmly in place so that they will not break during the forming process.

A still further object is to provide a machine from which the formed barrel or drum can be removed quickly without requiring 25 the disconnection of any of the parts.

A still further object is to provide a machine of this character which is constantly under the control of the operator and which can be actuated easily to form the barrels or 30 drums accurately.

With the foregoing and other objects in view which will appear as the description proceeds, the invention resides in the combination and arrangement of parts and in 35 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a side elevation of the ma- 45 chine.

Figure 2 is a plan view thereof, a portion of the feed table being removed.

Figure 3 is a section on line 3—3, Figure 1.

Figure 4 is a view partly in elevation and

partly in section of one of the units of the mandrel and showing the clamp closed.

Figure 5 is a similar view showing the clamp open.

Figure 6 is a section on line 6—6, Figure 4.

Figure 7 is a side elevation of one of the mandrel units showing that side opposite to the one illustrated in Figure 5.

Figure 8 is a plan view on a reduced scale 60 of one of the barrel members prior to being shaped.

Referring to the figures by characters of reference 1, 2 and 3 designate upstanding frame members connected by upper and 65 lower beams 4 and 5 whereby a rigid structure is provided. Bearings 6 are supported by the members 1 and 2 and journaled within these bearings is a shaft 7 having one end portion projecting across the space between the members 2 and 3 and into a large opening 8 provided in the member 3, said opening being concentric with the shaft as shown particularly in Figure 1. A gear 9 is secured to the shaft 7 between the bearings 6 and is engaged by a small drive gear 10 secured to a longitudinal shaft 11 which is journaled in the members 1, 2 and 3 and is provided at one end with a crank arm 12 or the like whereby the shaft can be rotated readily.

Keyed on and adjustable longitudinally of that portion of the shaft 7 between the members 2 and 3 is a series of mandrel units 13 each of which includes a segmental body 85 member 14 having a hub 15 concentric with the arcuate edge of the member and which engages the shaft 7. An ear 16 projects from this member 14 and is pivotally engaged by one end of an arcuate member 17 which bridges across the hub 15. Both of the members 14 and 17 have one face hollowed out or recessed and formed on the recessed side of the member 17 at that end remote from the ear 16 is a lug 18. The corresponding end of the member 14 has a shaft 19 journaled therein, this shaft carrying a cam 20 on the free end of which is provided a hook 21. The shaft 19 extends transversely through the members 14 of all of the 100

units and the various cams 20 are connected to this shaft by means of set screws 22. A handle 23 is attached to one end of the shaft 19 as shown in Figure 5.

5 Each of the members 17 is provided between the ends of its periphery with a transverse recess 24 adjacent which is an inwardly extending guide sleeve 25 integral with the member 17. Slidably mounted 10 within the guide sleeve 25 is a block 26 to the outer end of which is secured a gripping plate 27 adapted to extend into the recess 24 when the member 17 is in one of its 15 positions. Each block 26 has a slot 28 in its inner end provided with a cross pin 29 and this pin engages one end of an eye bolt 30 the other end of which is slidable in a bracket 31 secured to the hub 15. A nut 32 engages the bolt and serves to prevent its 20 withdrawal from the bracket 31. A coiled spring 33 is mounted on the bolt and bears at one end against the bracket and at its other end against the block.

A set screw 34' may be provided on each 25 hub 15 for engaging the shaft 7 to hold the hub against sliding movement on the shaft after it has been adjusted to proper position.

Pivottally connected to the members 2 and 30 3 are side strips 34 provided on their free end portions with adjustable weights 35. To each of these strips is pivotally connected a head 36 and the two heads are connected by parallel rollers 37 constituting pressers. 35 These rollers are adapted to contact with the units of the mandrel at points above the shaft 7.

One of the upper beams 4 is provided with longitudinal slots indicated at 38 and 40 adjustably mounted on each of these slotted portions is a block 39. Angular guide rails 40 are supported by the blocks and extend between the members 2 and 3. These guide rails are so spaced apart as to support the 45 ends of the staves or strips to be formed into a barrel.

A shaft 41 is journaled in the members 2 and 3 and has cams 42 secured thereto and located directly under the strips 34. A 50 crank arm 43 or the like is secured to the shaft and by rotating the same the cams 42 can be caused to shift the strips 34 upwardly so as to move the rollers 37 away from the units of the mandrel.

55 Under normal conditions the cams 20 are out of engagement with the lugs 18 and the handle 23 is extended upwardly and inwardly as indicated in Figure 5. Thus the members 17 of the units are swung toward the members 14, leaving the clamping plates 27 out of the recesses 24.

The strips or staves S to be formed into a drum or barrel are assembled with flexible bands or hoops B as shown in Figure 8, 65 these bands or hoops projecting at one end

beyond one of the end stays or strips. The assembled structure shown in Figure 8 is then placed on the guide strips or rails 40 and pressed forwardly until the first stave or strip S comes under the gripping plates 70 27 positioned as shown in Figure 5. It is of course to be understood that after the insertion of this stave or strip the handle 23 is swung outwardly to the position shown in Figure 4 with the result that all of the 75 cams 20 will press against the lugs 18 and thrust them upwardly into engagement with the hooks 21. Consequently the stave or strip engaging the plates 27 will be tightly clamped as shown in Figure 1. The rollers 80 37 are then lowered into engagement with the structure, one of the rollers bearing on the members 17 while the other roller bears upon the hoops or bands B. The operator then rotates the crank 12 and this will cause 85 the mandrel elements to rotate, pulling the staves and hoops therewith so that they will be caused to completely encircle the mandrel units, the projecting ends of the bands or hoops ultimately being brought to position 90 over the opposed ends where they can be nailed or otherwise secured. The handle 23 can then be swung inwardly so as to release the lugs 18 from the hook 21 and, consequently, the members 17 will promptly swing 95 inwardly out of contact with the staves adjacent thereto and the formed drum or barrel body can thus be withdrawn from the machine by pulling it longitudinally off of the collapsed mandrel and through the opening 8 in the member 3. By having the springs 33 the plates 27 can be thrust inwardly against the action of the springs so as to permit the formed barrel to be slid off of the plates readily.

100 By mounting the rollers 37 in pivoted heads 36, they act as equalizers for distributing pressure equally where the material to be shaped is first bent on the mandrel. Thus danger of cracking or breaking the 110 material is greatly reduced.

105 What is claimed is:—

1. In a machine for forming veneer barrels the combination with spaced mandrel units mounted for rotation, each unit including a segmental body member and an arcuate pivoted member, of gripping plates mounted on the body members, means for shifting the pivoted members for co-operation with the plates to engage one end of 115 the stock to be shaped into a barrel, spaced parallel rollers, and means for binding said rollers upon the stock throughout the width thereof and along parallel lines.

2. A machine for making veneer barrels 125 including rotatable mandrel units each having a segmental body portion and an arcuate pivoted portion, gripping plates, yielding means for connecting said plates to the body portions, means for simultaneously 130

shifting the arcuate portions relative to the body portions to bind one end of the barrel forming stock against the gripping plates, said plates being shiftable inwardly relative 5 to the arcuate portions when the barrel is removed.

3. In a machine for making veneer barrels a plurality of rotatable mandrel units each including a segmental body portion 10 and a pivoted arcuate portion, there being a recess in the periphery of each arcuate portion for the reception of one end of barrel forming stock, gripping plates movably connected to the body portions and yieldingly 15 supported adjacent the recesses, means for simultaneously shifting the arcuate portions toward the gripping plates to bind upon one end of the barrel forming stock projecting into the recesses, said plates being shiftable 20 inwardly into the recesses and relative to

the arcuate portions when the formed barrel is removed.

4. In a machine for forming veneer barrels rotatable mandrel members, means cooperating therewith for detachably gripping 25 one end of the stock to be formed into a barrel, heads pivotally mounted, parallel rollers carried by the heads, and yielding means for binding the rollers upon the engaged stock throughout the width thereof 30 to clamp the stock along parallel lines upon the mandrel members.

In testimony that I claim the foregoing as my own, I have hereto affixed my signature in the presence of two witnesses.

JOSEPH L. WALKER.
